UNITED STATES PATENT OFFICE

EDOUARD PORET, OF CALAIS, FRANCE

DESIGN FOR LACE

Application filed January 20, 1932. Serial No. 42,550. Term of patent 3½ years.

To all whom it may concern:

Be it known that I, EDOUARD PORET, a citizen of France, and a resident of Calais, France, have invented a new, original, and ornamental Design for Lace, of which the following is a specification, reference being had to the accompanying drawing, forming part thereof.

The figure is a plan view of a piece of lace, showing my new design.

I claim:

The ornamental design for lace, as shown.

EDOUARD PORET.
